US0D1008623S

(12) **United States Design Patent** (10) **Patent No.:** **US D1,008,623 S**
(45) **Date of Patent:** **** Dec. 26, 2023**

(54) **SHOE**

(71) Applicant: **NIKE, Inc.**, Beaverton, OR (US)

(72) Inventor: **Jordyn N. Klumpp**, Beaverton, OR (US)

(73) Assignee: **NIKE, Inc.**, Beaverton, OR (US)

(**) Term: **15 Years**

(21) Appl. No.: **29/887,589**

(22) Filed: **Mar. 22, 2023**

(51) LOC (14) Cl. **02-04**

(52) U.S. Cl.

USPC **D2/953**; D2/951; D2/960

(58) **Field of Classification Search**

USPC ..... D2/902, 906, 908, 916, 918, 925, D2/946–962, 977; 36/3 B, 22 R, 24.5, 36/25 R, 28, 32 R, 34 R, 59 C, 67 A, 103 CPC A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36

(57)

CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.
The broken lines and unshaded regions depicting the remainder of the shoe form no part of the claimed design.

1 Claim, 3 Drawing Sheets
